(57) **CLAIM**

The ornamental design for a shaving razor cartridge dispenser, as shown and described.

DESCRIPTION

FIG. 1 is a first perspective view of a design of a shaving razor cartridge dispenser of the present invention;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a back view thereof; and,

FIG. 8 is second perspective view thereof.

The dash broken lines are directed to the environment and are for illustrative purposes only and form no part of the claimed design.

1 Claim, 6 Drawing Sheets(56)
